tion of Maine

Application August 3, 1937, Serial No. 157,181

4 Claims. (Cl. 146—163)

The present invention relates generally to pickle slicing machines and is more particularly a machine having for its primary object an arrangement permitting the slicing of pickles either longitudinally or transversely, that is either lengthwise or crosswise of the pickles.

The invention relates more especially to a machine or apparatus of the type in which manually loaded pickle carriers are, by means of a flexible endless conveyor, successively fed to stationary slicing knives in the course of operation of the machine, it being understood that in this reference as well as the references hereinafter to pickles, it is intended to include raw cucumbers, carrots, beets, and in fact any vegetable or similar article capable of being divided into slices in the manner contemplated by the present machine.

Among the further objects of the invention is the provision of an apparatus in which readily interchangeable parts insure similarly effective operation in either the lengthwise or crosswise slicing of the commodity.

A still further object is the provision of a cutting arrangement adapted to effectively hold the articles being sliced, during the slicing operation as well as one in which each individual knife or cutting blade is held in a manner which will permit of its quick detachment for sharpening and in case repairs are necessary.

A still further object of the invention is the provision of a pickle slicer which, in general, is of a simple, inexpensive construction, involving parts capable of ready removal for purposes of repair and substitution, and insuring speedy, accurate operation.

With these general objects in mind, the further and more specific objects of the invention as well as the construction, arrangement and operation of its several parts, will be better understood and more thoroughly appreciated from the following detail description thereof, in reference to the accompanying drawings which form a part of this specification and in which

Figure 1 is a side view of the machine with the parts in position for the crosswise slicing of pickles and the like.

Figure 2 is a similar view showing a modified structure adapting the machine to the lengthwise slicing of pickles and the like.

Figure 3 is a fragmentary detail cross section taken on line 3—3 of Figure 1.

Figure 4 is a similar view taken on line 4—4 of Figure 2.

Figure 5 is a fragmentary horizontal section taken on line 5—5 of Figure 3.

Figure 6 is a detail vertical longitudinal section taken on line 6—6 of Figure 5.

Figure 7 is a horizontal sectional view taken on line 7—7 of Figure 4.

Figure 8 is a vertical longitudinal section in detail taken on line 8—8 of Figure 7.

Figure 9 is a detail perspective view of the crosswise cutter and one of the pickle carriers with which this cutter cooperates, and

Figure 10 is a detail perspective view of the lengthwise cutter and one of the carriers with which it cooperates.

Referring to these figures and particularly to Figures 1, 3, 5, 6 and 9, the invention proposes a machine which includes upper spaced parallel horizontal angle bars 15 forming the longitudinal side rails of the main frame, rigidly connected and supported by legs or uprights 16 in connection with diagonal or inclined braces 17.

The lengthwise disposed parallel angle bars 15 forming the table, are also connected by a plate 18 forming the table top, having flanges 19 along the opposite sides thereof, and this plate 18 may be enameled, chromium plated, or otherwise provided with a surface capable of being readily cleaned and maintained in a clearly, sanitary condition.

At opposite ends of the frame top, rollers 20 and 21 are mounted in bearings 22, around which an endless flexible belt 23 is trained so that its upper run passes from the roller 20 at the receiving end of the table to the roller 21 at the discharge end of the table, in the direction of the arrow 24 in Figure 1, the lower run of the belt passing in the opposite direction beneath the table top.

At the discharge end of the frame adjacent to and above roller 21, a frame 25 rises for the support of a motor 26, the switch of which is indicated at 27. This motor, through a suitable reduction gear and through a chain or belt drive 28, preferably housed in a casing 29, actuates the roller 21 so that movement in the direction previously stated is thus imparted to the belt or flexible carrier 23.

Secured at suitable spaced points upon the belt 23 are a series of carriers, as generally indicated at 30 in Figure 1, the details of which appear in Figures 3, 5, 6 and 9.

Each of the carriers 30 is secured transversely across and projects at its ends laterally beyond, the belt or flexible carrier 23, and each, held to the belt by means of rivets and the like as seen at 31 in Figure 6, has a flat base 32 provided with a series of grooves 32a paralleling the longitudinal

axis of the belt. Each carrier has side walls 30^a which increase in height toward the rear thereof and each has a rear wall 33 which presents a series of slots forming continuations of the base 5 grooves 32^a, and a series of upstanding teeth 33^a which upper ends are enlarged to extend forwardly and thus present an undercut forward surface on the rear wall conforming somewhat to the rounded contour of the article to be sliced, 10 all as best seen in Figure 9.

Near the discharge end of the belt and adjacent to the upright frame 25 is a combined cutter and guide frame consisting of longitudinally spaced inverted U-shaped brackets 34 and 35, 15 to the upper and side portions of which are adjustably connected the laterally projecting threaded stems 36 and 37 of the parallel spaced apart upper and side guide rails 38 and 39.

The forward ends 40 of the side guide rails 20 are laterally flared or outwardly curved and the forward ends 41 of the top guide rails 38 are upwardly curved or flared so that as each carrier 30 approaches the forward bracket 34 of the 25 guide and cutter or slicing frame, it passes beneath the upper guide rails 38 and between the side guide rails 39 whereby its plurality of base grooves and rear wall slots will be effectively and certainly positioned with respect to the guide frame and with respect to the slicing cutters or 30 knives stationarily held in this frame in a manner which will be presently described.

Bolted to the upper horizontal portion of the forward frame bracket 34 as most plainly seen by reference to Figures 3, 5 and 6 as by means 35 of bolts 42 is a rearwardly tapering approximately triangular knife block 43, the inclined sides of which are cut away to present a plurality of stepped knife or blade seats inclining rearwardly and downwardly as indicated at 44 so that each 40 seat presents to the upper forward edge of its respective knife or blade 45 a bearing shoulder limiting rearward movement of the downwardly and rearwardly inclined cutting portion of the 45 blade.

Thus each blade may be held in place by a single fastening screw 45^a so that where necessary it is an easy matter to remove the knives or blades for sharpening. Preferably the blades 45, as seen in Figure 9 have their forward edges 50 provided with a single bevel 47 and in operation as seen in Figure 6, their lower ends trail through the base grooves 32^a of the carriers as the latter pass the knives, the trailing blades engaging the pickles or other articles to be sliced and by their angle with respect thereto serve to hold the article firmly against displacement, between the cutting edges of the blades and the undercut in the surfaces of the rear walls of the carriers, the blades passing through the slots and thus between the teeth constituting these walls.

It will be observed that the knife block 43, which is bodily removable from the bracket 34 by detaching bolts 42, tapers in the direction of movement of the carriers so that each pickle, as 55 its carrier passes beneath the knife block, is initially engaged by the two most widely laterally spaced blades 45, provided of course the pickle is of sufficient length to be so engaged. At any rate each pickle will be initially engaged adjacent its opposite ends and the full force and effect of the steadyng and holding of each pickle is thus initially brought into play so there is no tendency of the pickle to thereafter shift or displace as it is rapidly sliced from its outer ends 70 to its center. Thus a uniform slicing of each

pickle is assured and as each slice is cut it is free to separate laterally from the unsliced central portion of the pickle, especially in view of the single bevel 47 of the cutting edges of the blades.

The brackets 34 and 35, to which the guide 5 runners 38 and 39 are connected so as to effectively guide the several pickle carriers vertically and laterally in insuring complete registration of the knives or blades 45 with the base grooves and rear wall slots of the carriers, are held by means of bolts 48 and 49 to the sides of the main frame and, since the ends of the pickle carriers 30, as previously described, project laterally beyond the sides of the belt 23, the upper surface of the top plate 18 is preferably provided 15 with slide rails 50 which may be of the half round form shown particularly in Figure 3 and on which the ends of the pickle carriers slide so that the belt 23 to which the pickle carriers are attached is maintained above the surface of the 20 frame top plate 18.

Provision is preferably made for quick detachment of the belt 23 and this may be accomplished by a quick detachable coupling 51 at any suitable point in the belt, as indicated in Figure 1, 25 any one of the more well known belt couplings being capable of adoption for this purpose.

Thus in order to easily and quickly displace the entire arrangement previously described for slicing pickles crosswise, it is merely necessary 30 to remove the guide and cutter frame by detaching bolts 48 and 49 thereof from the main frame so that the brackets 34 and 35, with knife block 43 and the pickle carrier guides 38 and 39 may be removed as a unit. Then by detaching the 35 belt coupling 51 the entire belt 23 with its plurality of pickle carriers 30 may be withdrawn from around the rollers 20 and 21.

The purpose of the above is to permit of the use of substitute parts of generally the same nature providing for the longitudinal slicing of pickles. In this arrangement a similarly coupled but somewhat more narrow belt 52 is employed, having a plurality of pickle carriers 53 securely fastened thereon which are substantially less in 45 width than the before described carriers 30 and elongated lengthwise of the belt in view of the necessity to accommodate the pickles or objects to be sliced with their longitudinal axes parallel to that of the belt.

Thus in the modified construction provided for lengthwise slicing the belt 52 will preferably slide upon a single flat slide rail 54 bolted as at 55 in Figure 4 through the top plate 18 along the median line of the latter.

Moreover, as shown in Figures 2, 4, 7, 8 and 10, the belt 52 may be easily applied around the rollers 20 and 21 after installation of the central flat slide rail 54, and the belt connected by its coupling indicated at 56 in Figure 2 so that the upper run of the belt rests upon the slide rail for substantially the full length of its upper run and needs but angular guide rails 57 to engage the sides of the carriers 53 for effective guidance of the latter.

The carriers 53 are preferably formed of plates with bent up sides 58, and with a series of rods 59 laid in spaced parallel relation upon the upper surface of such plates and spot welded or otherwise rigidly secured thereto so that these rods 70 form between them the base grooves. At the rear ends of the carriers, the rods thereof are bent upwardly and slightly forwardly and doubled upon themselves to form a series of teeth, the series of which constitute the rear wall whose 75

inclination effectively holds the pickles in cooperation with the inclined stationary knives to be presently described. These upwardly bent inclined and doubled rear ends of the rods are best seen at 60 in Figures 8 and 10.

5 The brackets 61 and 62 are shaped and attached to the frame by bolts 63 and 64 in the same manner as the before described brackets 34 and 35 and the angular guide rails 57 are carried by threaded adjusting rods 65 and 66 adjustably bolted to the sides and tops of these brackets as shown in Figure 4.

10 The knife block 67 as best seen in Figures 8 and 10 has a cross piece 68 by means of which it is bolted to the top portions of the brackets 62 and 62 and, like the before described knife block 43, is tapered in the direction of movement of the pickle carrier so as to present stepped surfaces upon which the upper ends of the knives or 15 blades 69 are secured by single bolts 70 against inclined shoulders which effectively prevent rocking movement of the blades as they pass through the pickles. The knife block 67 is thus the same as the knife block 43 on a substantially reduced 20 scale, being reduced both in length and width in view of its necessity to support but a few blades 69 for the longitudinal slicing of pickles as compared to the blades 45 of the block 43 for the cross slicing of the pickles.

25 30 Otherwise than as just above stated the operation is exactly the same for the longitudinal slicing of the pickles as it is for the cross slicing thereof, the pickles being sliced from the sides to the center so that the slices are free to fall 35 away and clear the knives or blades in the course of the slicing operation.

35 Obviously in the use of either the longitudinal or cross slicing equipment, the pickle carriers in rounding the roller 21 at the discharge end of the apparatus, discharge the sliced pickles in a 40 downward direction and this discharge may be effected upon a conveyor 71, a portion of which is shown in Figures 1 and 2, common of course to both lengthwise and crosswise slicing equipment, by 45 means of which the sliced pickles may be transported to a distant point. In the course of movement of the sliced pickles along conveyor 71, it is obvious the slices may be inspected by attendants and the side or end pieces removed where 50 the sliced pickles otherwise pass inspection.

55 It is obvious that in connection with either the lengthwise or crosswise slicing of pickles according to the present invention, the effective guidance of the pickle carriers by means of guides rigidly in a unit with the slicing blades or knives, insures a complete effective registration at all 60 times as between these knives or blades and the base grooves and rear wall slots of the several carriers so that there is little if any danger of breakage of parts and the cutting edges of the blades or knives will be preserved except from ordinary dulling in use. Any individual blades or knives may be easily and quickly replaced by 65 detaching the single holding screw thereof, while it is obvious that by detaching the knife block, substitution of the complete knife assembly is easily effected. With these collective features it is obvious the machine as a whole is not only 70 capable of effective operation with speed and certainty, but will be durable in use, may be easily and quickly cleaned, and is adaptable to quick interchange of parts for longitudinal as well as cross slicing of the pickles.

75 What is claimed is:

1. A slicing machine comprising a main frame

including a horizontal top portion, a pair of rollers at opposite ends of the frame, a detachably coupled endless member trained around said rollers with its upper run movable above and along the top portion of the main frame, a series of carriers secured along said endless member for movement with the upper run thereof from the receiving to the discharge end of the frame, a frame rising from the main frame adjacent to the discharge end thereof, a motor supported by 10 the latter frame and having geared connection with the roller at the discharge end of the frame, a combined guide and cutter frame including inverted U-shaped brackets detachably connected to the main frame at longitudinally spaced points 15 near its discharge end and each having portions extending above and across the upper run of the endless member to bridge the moving carriers, guide rails each having upstanding and outstanding rods respectively extending through, 20 and adjustably in connection with the top and side portions of both of said brackets to engage and effectively guide the successive carriers in their movement through the guide frame, the guide rails also forming bracing connections between the said brackets, a knife block detachably supported in said guide frame, and a plurality of blades connected to and depending from the knife block for cooperation with the carriers to slice articles carried by the latter, the carriers 25 having vertically slotted upright walls, the slots of which register with the said blades.

2. A slicing machine comprising a main frame including a horizontal top portion, a pair of rollers at opposite ends of the frame, a detachably coupled endless member trained around said rollers with its upper run movable above and along the top portion of the main frame, a series of carriers secured along said endless member for movement with the upper run thereof from the receiving to the discharge end of the frame, a frame rising from the main frame adjacent to the discharge end thereof, a motor supported by 30 the latter frame and having geared connection with the roller at the discharge end of the frame, 35 a combined guide and cutter frame including inverted U-shaped brackets detachably connected to the main frame at longitudinally spaced points near its discharge end and each having portions extending above and across the upper run of the 40 endless member to bridge the moving carriers, guide rails each having upstanding and outstanding rods respectively extending through, and adjustably in connection with the top and side portions of both of said brackets to engage and effectively guide the successive carriers in their movement through the guide frame, the guide rails also forming bracing connections between the said brackets, a knife block detachably supported in said guide frame, and a plurality of 45 blades connected to and depending from the knife block for cooperation with the carriers to slice articles carried by the latter, the carriers having vertically slotted upright walls, with the 50 slots of which the blades are registered, each of the said walls presenting an undercut surface toward the blades and the blades being supported at a trailing angle with the carriers for cooperation with the undercut surfaces of the carrier walls to firmly hold articles within the carriers 55 during the slicing operation.

3. A slicing machine comprising a main frame including a horizontal top portion, an endless member detachably in connection therewith having its upper run movable lengthwise on the top 60

portion of the frame, means for driving said endless member, a guide and cutter frame detachably in connection with the said upper portion of the main frame including a pair of inverted U-shaped brackets bridging the upper run of the endless member and in longitudinally spaced relation, a plurality of article carriers secured along the endless member for passage with the latter through said brackets, guide rails extending along and carried by both brackets to engage and guide the carriers in their passage therethrough and having outstanding and upwardly adjusting rods in adjustable connection with the side and top portions of the brackets, a knife block in detachable connection with the top portion of one of said brackets and having its sides tapering in the direction of movement of the carriers and provided with series of stepped blade seats, and blades detachably secured at their upper ends in said seats and depending angularly from the block in the direction of movement of

the carriers, whereby the entire guide frame including the guide rails and cutter block with its cutters may be detached as a unit, the carriers having means forming generally upright walls and presenting a series of slots in line with the blades. 5

4. In a slicing machine, a plurality of moving article carriers, each having side walls and a generally flat face, a plurality of rods secured in parallel relation upon the upper face of the base to form parallel grooves therebetween from the front to the rear, the rear ends of said rods having upwardly bent portions forming an upstanding article support presenting a plurality of slots in alignment with the said grooves, the upwardly bent rear portions of the rods being forwardly inclined and doubled upon themselves with their extremities depending against the rear portion of the flat face of the carrier. 10 15
